D. Christensen

(21) Appl. No.: **29/136,199**

(57) **CLAIM**

(22) Filed: **Jan. 25, 2001**

The ornamental design for a user interface for a television
display screen, as shown and described.

(51) **LOC (7) Cl. 14-02**

DESCRIPTION

(52) **U.S. Cl. D14/486**

(58) **Field of Search D14/485-95; D18/24-33;
D19/6; D20/11; D21/324-33; 345/326,
339-58**

FIG. 1 is a front view of a user interface for a television
display screen showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and,

FIG. 6 is a front view of a sixth embodiment thereof.

The broken line drawing of a television display screen in all
views is for illustrative purposes only and forms no part of
the claimed design.
